UNITED STATES PATENT OFFICE.

CHARLES ALBERT THOMPSON, OF GALVESTON, TEXAS.

LETTER-COPYING PRESS.

SPECIFICATION forming part of Letters Patent No. 399,583, dated March 12, 1889.

Application filed December 30, 1885. Serial No. 187,157. (No model.) Patented in England March 9, 1885, No. 3,077; in Canada May 13, 1885, No. 21,667, and in France June 16, 1885, No. 169,392.

To all whom it may concern:

Be it known that I, CHARLES ALBERT THOMPSON, of Galveston, in the county of Galveston and State of Texas, have invented 5 a new and useful Improvement in Apparatus for Copying Letters and other Written Documents, (for which Letters Patent were granted to me in England March 9, 1885, under No. 3,077; in France June 16, 1885, under No. 10 21,667, and in Canada May 13, 1885, under No. 169,392, and in Canada May 13, 1885, under No. 21,667;) and I do hereby declare that the following is a full, clear, and exact description of the same, reference being had to the accompanying drawings.

15 The object of this invention is to provide improved means for copying letters and other written documents, so that the copying may be accomplished more easily and quickly than by means of an ordinary copying-press in the usual manner, and so that the copy can be put into compact form for ready reference; and the novelty consists in the construction and combination of the several parts, all as will now be more specifically set forth.

20 In the accompanying drawings, Figure 1 represents an isometrical perspective view of my improvement. Fig. 2 is a side elevation with frame removed. Fig. 3 is a detail in longitudinal vertical section showing means 25 for supporting the roll of copying-paper; Fig. 4, detail showing boss-rods adjustable by set-screws.

Similar letters of reference indicate the same parts in all the figures.

30 A and A' represent two rollers, which are journaled at each end and one above the other in suitable standards, a a' ; attached to a suitable base or table, B. One of said rollers may be of metal or other substance, and 35 the other of a substance slightly elastic, so as to yield slightly under pressure. These rollers are placed in contact with each other, so as to impart a considerable degree of pressure on the paper which is passed between them, as hereinafter described; but in the 40 drawings they are represented as being slightly apart, for the purpose of more clearly showing the construction of the apparatus.

45 C represents an ordinary roll of thin copying-paper, which may be of any of the kinds used in the common copying-presses and of

suitable length. Into the hollow ends of this roll the pointed bosses D enter from each side when the roll is placed between the vertical standards a' on the left-hand side of the table B, as shown in the drawings. These bosses are each fixed on rods r , screw-threaded at the ends where they pass through the upper ends of said standards a' a' . By means of said screw-threads the said bosses can be advanced 55 forward or drawn in, as may be required, in fitting the roll of paper into position for use. As thus mounted on said bosses the roll is free to turn easily as may be needed in feeding the web for use in copying.

60 If desired, the rod r , instead of being screw-threaded, as above described, may be adapted to slide in and out of slots in the standard and each be held in any desired position 65 therein by means of a set-screw, as shown in Fig. 4.

65 II is a trough for water, into which the roller A' is immersed at its lower side when the press is in use. I is a small roller between the roll and the roller A' and in close proximity to this roller A', and is journaled in the horizontal bracket a^2 , extending from the vertical standard a . It is of special use in pressing the paper upon the dampening-roller A', and thus squeezing it and giving it the proper 70 degree of dampness for copying and also for insuring smoothness in the paper as it passes 75 in the sheet c from the roll C between the rollers A' and A. As the paper in this sheet form c passes over the roller A', which has 80 been moistened by the water in the trough II, the paper will be ready in a dampened and smooth condition to receive the impression from the written page as it is fed down upon 85 said sheet c from the table K. The table K 80 is inclined and has its lower edge near the roller A', and is supported by the arms k at its sides, which are attached upon the top of the vertical standard a . This arrangement 90 of the copy-table is of special advantage in 95 many particulars. Among others its inclination aids in some degree in automatically feeding the written-page roller A and A', and it is placed where it is most convenient for use, and it is also arranged in respect to the 90 body of the press in the most compact and attractive way. The written page having been

fed with its inked side toward the sheet *c* upon said sheet, the two are carried between the rollers *A* and *A'* as said roller *A'* is revolved by the crank *F*. These two rollers are

5 in practice placed so near together that the revolution of the roller *A'* will by friction operate to turn the roller *A*. As the sheet *c* and the written page pass between and by the rollers *A* *A'* they come between the rollers *A* 10 and *E'* and then between the rollers *E* and *E'*. The said rollers are journaled in brackets *a*³, and they are moved by the revolutions of roller *A'*, the power of which is transmitted by friction. The office of said rolls is 15 very important, as by means of these rollers the sheet *c* and the written page are drawn evenly and smoothly between the rollers *A* and *A'* under any and all conditions of use.

The operation of the device is as follows:

20 The roll of paper *C* having been adjusted on the bosses *D* *D'*, as the crank *F* is turned revolving the roller *A'*, the end of the sheet *c* from said roll is now passed between the rollers *I* and *A'* and the written paper is fed from 25 the inclined table *K* down upon the sheet *c* and carried along with it between the rollers *A'* and *A*. The sheet *c* is sufficiently moistened by contact with the dampened surface of the roller *A'* to insure, under ordinary conditions, the copying of the writing upon the sheet *c*. As the sheet *c* and the written page pass from between the rollers *A'* and *A* they come between the rollers *A* and *E*, which act to draw them evenly and smoothly forward, 30 and so on between the roller *E'* and *E*, by which substantially the same purpose is accomplished. While I prefer to use the roller *E*, it is not absolutely essential to do so.

It will thus be observed that the paper on 40 which the copy is to be made is kept even and smooth while being dampened, and that only the requisite quantity of moisture is taken by it, and that in the process of copying both papers are kept even and smooth, and thus the 45 copied paper comes off the last rollers in a good condition for use in mailing or otherwise.

The operation is as follows: A web or roll of copying-paper, *C*, is placed so that it hangs by its center on bosses *D* and *D'*, which are 50 adjusted by means of the screw-rods *rr*, and the end of sheet *c* passed between rollers *I* and *A'*, and then between the rollers *A* and *A'*, then between rollers *A* and *E'*, and thence between *E'* and *E*, and the trough *H* being 55 partly filled with water to moisten roller *A'*, the letter is then pushed from the table *K* toward rollers *A* and *A'*, and the crank *F*, attached to *A'*, being turned to rotate the rollers, they will carry the paper forward. The 60 paper *C* is sufficiently moistened by roller *A'* to receive a good impression and carried forward by rollers *E* and *E'*. When the paper *C* is entirely used, a new web or roll of copying-paper is placed on bosses *D* and *D'* and

the operation, same as above, is repeated. 65 The paper *C*, after passing between *E* and *E'*, can be torn in sheets and filed in any convenient form.

I am aware that heretofore in copying-presses the paper has been fed from a revolving roll and duly dampened by passing over suitable rollers, and that the written sheet has been fed or placed upon said paper and a copy taken as the written sheet and the copy-paper passed between rollers, and that 70 provision has been made in such devices for moistening one of said rollers, and also means provided for feeding the written sheets upon the paper to be copied; and I am also aware that heretofore means have been used to adjust rollers by movable supports or journal-bearing at their ends, and I therefore do not broadly claim any of the features as being 75 my present invention.

I am also aware that it is not new to provide a feeding-table in printing-presses and many other like devices; but

What I do consider new, and desire to secure by Letters Patent, is—

1. In a copying-press, as described, the combination of the dampening-roller *A'*, moistened in the manner described, with the smoothing-roller *I* at one side of and in close proximity to it and situated between said dampening-roller and the roll of paper, and the 90 roller *A*, journaled in the standard *a*, and the smoothing-rollers *E* *E'*, placed at one side and beyond the rollers *A* and *A'* and journaled in brackets *a*³, the several parts made and all 95 arranged and combined in the manner and 100 for the purposes described, whereby the paper is evenly and smoothly moistened before the copy-paper is applied and both are kept smooth during the process of copying.

2. The combination, with the frame *B*, having 105 roller *I*, journaled in brackets *a*³ in close proximity to roller *A'*, and rollers *A* *A'*, journaled in standards *a*, and roller *E'*, journaled in bracket *a*³ and the trough *H*, and the inclined copy-table *K*, the edges of which are contiguous to the roller *A*, substantially as and for the purposes set forth.

3. The combination of the water-vessel, the squeezer-roll at the side of the dampening-roll, and the copy-press roll directly 115 over the dampening-roll, substantially as described.

4. In a copying-press, the combination of the press-copy roll with the dampening and the squeezer rolls, whereby the copying is 120 done between the dampening-roll and the press-copy roll after the surplus moisture has been removed from it.

CHARLES ALBERT THOMPSON.
